ELECTRIC LANTERN

Fredrick J. Kirkman, Freeport, Ill., assignor to Burgess Battery Company, Freeport, Ill., a corporation of Illinois

Application October 10, 1956, Serial No. 43,292

Term of patent 14 years

(Cl. D48—24)

Fig. 1 is a front elevational view of the electric lantern showing my new design;

Fig. 2 is a side view; and

Fig. 3 is a top view of the electric lantern.

The essential features of my design reside in the portions shown in full lines.

I claim:

The ornamental design for an electric lantern, substantially as shown and described.
